L. F. WARREN.

SAFETY RAZOR.

APPLICATION FILED NOV. 11, 1915.

Patented Dec. 18, 1917.

UNITED STATES PATENT OFFICE.

LUKE FRANCIS WARREN, OF NEW YORK, N. Y., ASSIGNOR TO THE DARRENT COMPANY, INC., A CORPORATION OF NEW YORK.

SAFETY-RAZOR.

1,250,398.

Specification of Letters Patent. Patented Dec. 18, 1917.

Application filed November 11, 1915. Serial No. 60,842.

To all whom it may concern:

Be it known that I, LUKE FRANCIS WARREN, a citizen of the United States, residing in the city, county, and State of New York, 5 have invented certain new and useful Improvements in Safety-Razors, of which the following is a specification.

This invention aims to provide a certain improved style of safety razor in which the 10 blade is given a reciprocating or similar motion while it is being drawn over the face of the user. Such a motion causes the razor to cut more easily and without pulling the hair and is secured according to my invention 15 by mechanism of the simplest sort which is easily accessible for cleaning and which can be worked without special effort by the operator in the act of drawing the razor over his face.

20 The accompanying drawings illustrate an embodiment of the invention.

Figure 1 is a side elevation and Fig. 2 a rear elevation of the assembled razor;

Fig. 3 is a transverse section through the 25 head of the same;

Fig. 4 is a plan, partly broken away, showing the head of the razor and the parts mounted thereon, being taken on the line 4-4 of Fig. 1;

30 Fig. 5 is a section on the line 5-5 of Fig. 1 (Fig. 3 is shown on a scale larger than the other figures).

Referring to the embodiment of the invention illustrated the razor blade A is 35 mounted on a back B with its edge overlying a guard C of any usual or suitable design. The back is provided with undercut end lugs D which fit into similarly shaped notches in the end of the blade. The blade 40 is fastened on the back by means of a clamping member E having beveled ends which are forced under the undercut edges of the lugs D and thus pressed down on the blade; the clamping member E being forced inward from the rear until the ears F thereof are stopped by striking the lugs D. The means thus described for mounting and fastening the blade on the back are not claimed as a part of the present invention, being 45 covered in a co-pending application which I have filed. Various other styles of back and clamping means and blade may be used without departing from the present invention.

55 The back B is movably mounted on the

head G of the razor which is fastened on the upper end of the handle H at a suitable angle for convenient shaving. The head G is approximately U-shaped in transverse section. The back B rests on the top or front 60 face thereof and has an undercut or dovetailed lower portion which is guided longitudinally in undercut grooves J of the head, so that the back, with the razor clamped thereon may be reciprocated across the direction of shaving.

Reciprocation is effected by means of an eccentric pin K working in a transverse slot L in the back and mounted on a disk M which is rotatably carried in suitable bearings in the head and is rotated by means of a pinion N driven by an actuating rack which is transversely reciprocable in the head G. The length of the rack and the diameter of the pinion are such that for one 70 complete stroke of the rack there is somewhat more than a complete rotation of the pinion and, therefore, more than a complete reciprocating movement of the back and the blade carried thereby. That is to say, the 75 pinion and the crank pin transmit the motion of the actuating member O to the blade at an increased rate of reciprocation. The rack O is connected to an operating arm by means of a pin or screw P passing through a slot Q in the back of the head G. The operating arm is a long spring R extending from its connection with the rack to the lower end of the handle H and forming practically a part thereof. The handle is 80 provided with an offset portion S over which the operator can hook his first finger to get a better grip, while bearing with his thumb against the outside of the spring arm R, the latter being shaped with a broadened portion T at a point where the operator can conveniently press it with his thumb.

In operation, as one draws the razor down along his face one at the same time naturally grips the handle and presses the spring arm R inward, loosening his grip at the end of the stroke and letting the arm R out again. Thus there is caused by a natural and easy movement synchronous with the regular drawing movement, a reciprocation 95 of the actuating rack O which in turn causes a similar motion at an increased rate of speed of the blade.

I have found in practice that with such a reciprocation of the blade there is greater 100 105 110

danger of cutting one's self than where there is no such reciprocation; the skin which may be tough enough to resist a direct pull of the edge of the blade against it cannot 5 resist a saw-like motion of this sort. With safety razors having stationary blades there is, therefore, little danger of one's cutting oneself and one may press the blade against the face with considerable pressure,—an expedient which is often resorted to in order 10 to shave more closely than otherwise. Also to secure a closer or rougher shave the blade has been made in such razors adjustable toward and from the guard, and a considerable 15 space can be left without danger of cutting one's skin. But with the razor of the present invention the blade cuts with extreme ease and it is of the greatest importance that it be not permitted to press into the skin; 20 otherwise a cut face will result. I have provided against this difficulty by making the guard C adjustable in relation to the edge of the blade so that the guard can be set in such a position as to hold the edge from 25 pressing into the skin. The prongs of the

guard are mounted on a plate U carried by a pair of pins V which extend through the head G and are fastened at their rear ends to a yoke W which is carried between collars on a screw X which screws into the 30 back of the head and is provided at its outer end with a double milled head Y. By turning the screw X in one way or the other the guard can be set exactly to the desired relation with the edge of the blade. 35

What I claim is—

A safety razor having a head on the upper end thereof, a substantially U shaped handle H comprising a rigid side connected to the head, an actuating rack O mounted in said head, the flexible side of said handle being connected thereto, a disk M, a pinion N mounted thereon rotatable by the reciprocating movement of the rack, a blade A movably carried by the head and an eccentric 40 pin K for transmitting the movement of the disk to the blade. 45

In witness whereof, I have hereunto signed my name.

LUKE FRANCIS WARREN.
